UNITED STATES PATENT OFFICE.

WILLIAM MILLER DIGHT, OF GROVE CITY, PENNSYLVANIA.

WINDOW-SASH HOLDER.

1,073,595.

Specification of Letters Patent. Patented Sept. 23, 1913.

Application filed April 28, 1913. Serial No. 764,100.

To all whom it may concern:

Be it known that I, WILLIAM M. DIGHT, a citizen of the United States, residing at Grove City, in the county of Mercer and 5 State of Pennsylvania, have invented certain new and useful Improvements in Window-Sash Holders, of which the following is a specification.

This invention relates to new and useful 10 improvements in window sash holders.

An object of this invention is the provision of a means whereby the window sash when raised can be locked at any desired height.

15 Another object of this invention is the provision of a device which will answer all the necessary requirements of a lock for any window sash, the same being adapted to retain the sash in any desired position.

20 With these and other objects in view, this invention consists of certain novel constructions, combinations and arrangements of parts, to be hereinafter more fully described, claimed and illustrated in the accompanying 25 drawings in which:—

Figure 1, is a fragmentary sectional view of a window sash showing my invention applied, Fig. 2, is an enlarged fragmentary sectional view, of a portion of a sash showing the locking means, and Fig. 3, is a perspective view of my improved catch.

Referring to the accompanying drawings by similar characters of reference, the numeral 10 denotes in general a section of a 35 window sash and 11 the window frame which consists of the side panels 12, cleat or sash guide 13 and sill 14. The cleat or sash guide 13 has a vertical track 15 formed therein which at suitable intervals is notched 40 as at 16 the outer edges of which are wedge shaped as at 17 so as to catch the head or barbed portion 18 of the latch 19 which is secured to the window sash 20 by a screw 21 or other similar fastener. This latch 19 is 45 L shaped at its lower extremity as at 22 having the said barbed portion 18 formed on its end, while its front and rear edges are curved as at 23. The front curved face 23 terminates into a shoulder 24 which has 50 bosses formed thereon as at 25 to act as a pivot for the said latch 19 to operate on, and to keep the same from coming in frictional contact with the window sash 20, while

the rear curved edges terminate in a finger piece 26, for the convenience of the operator. 55

The notches 16 are reinforced by U shaped strips of material 26', one of the legs 27 of the U shaped member being driven into the wood of the sash guide 13 as clearly illustrated by Fig. 2, of the accompanying drawings, while the other leg 27 of the U shaped member is clamped snugly against the inner face of the notches 16 formed in the track 15 and is wedge shaped in formation on its outer end as at 17, to conform to the shape 65 of the notch 16.

The operation of the device is as follows:— To raise the window sash 20 the operator first must release the finger piece 26 by pulling up on same, upon which movement the 70 barbed end 18 is released from the notches 16. The face 29 of the barb 18 is rounded and consequently upon raising or lowering the sash 20 rapidly, the rounded face 29 of the barb rides freely in the track 15 without 75 entering the notches 16. Upon raising or lowering the sash 20 slowly the finger piece 26 which also answers the purpose of a weight forces the barbed head 18 of the latch 19 against the bottom of the track 15 80 and upon coming in contact with the first notch 16 in its path, the said head 18 is forced therein thus forming a locking means. It should be understood in this connection that various minor changes can be resorted 85 to within the scope of the appended claim without departing from or sacrificing any of the advantages of the invention.

Having thus fully described this invention what I claim as new and desire to protect 90 by Letters Patent is:—

The combination with a sash holder of a latch L shaped in formation having a barb at one extremity, the said barb having a rounded outer face, a finger piece for operating the latch, bosses upon said latch, a track having notches therein, reinforcements for the said notches, consisting of U shaped members, and a wedge shaped entrance to the notches. 95

In testimony whereof I affix my signature in presence of two witnesses.

WILLIAM MILLER DIGHT.
